RADIO RECEIVER

Emile Labin, New York, N. Y., assignor to Federal Telephone and Radio Corporation, a corporation of Delaware

Application July 3, 1942, Serial No. 449,595

10 Claims. (Cl. 250—20)

1

This invention relates to receiver systems and more particularly to time modulated impulse receivers.

For the purpose of economy in power and for preservation of a modicum of secrecy transmission of energy by time modulated impulses has been resorted to as described in United States patents to A. Reeves, Nos. 2,266,401 and 2,256,336 and United States patent to E. Deloraine and A. Reeves, No. 2,262,838. A particularly valuable type of such systems from the standpoint of avoiding interception of the messages is that described in my copending application entitled "Pulse modulation system," Serial No. 386,282, filed April 1, 1941, and in the copending application of E. Deloraine and myself entitled "Pulse transmission system," Serial No. 425,108, filed December 31, 1941. In accordance with this proposed system successive pairs of impulses are used to define a signal increment by simultaneous displacement of the impulses toward or away from each other in accordance with signal amplitude. The impulses are modulated between two limits, one limit of displacement being selected preferably to represent a constant timing of the successive impulses and the other limit representing a given displacement of the impulses (the impulses of each pair being displaced toward or away from each other in push-pull relation) with respect to said constant timing limit. The time displacement of the impulses, however, is very small compared to the time interval between successive impulses so that the period defined by either odd or even impulses may appear substantially constant.

A receiver may then be used in which is provided a selective circuit tuned substantially to a harmonic of the period. The harmonic is so chosen that the interval spacing between impulses of a pair at one extreme position of modulation, such as at the constant timing limit of the successive impulses, is an odd number of half wavelengths whereupon zero energy is passed by the filter. At the other extreme position of modulation, the interval spacing between impulses of a pair is such that considerable energy is passed by the filter. At the normal unmodulated position of the impulses, energy at a level intermediate the two extremes, passes the filter. Thus, by simple filtering and detecting, it is possible to receive the signals.

In order to receive the signals, a harmonic which will work properly with the given interval of the impulse pairs and the period between the pairs must be chosen. If the normal impulse

2

spacing is chosen so that the spacings between impulses of the pairs and between the pairs of impulses approach equality, any odd harmonic will be capable of use for detecting the signals.

5 In practicing this system, a relatively high harmonic is generally used. The energy level of a high harmonic is generally rather low requiring very sensitive detecting equipment. Furthermore, the signal to interference ratio may be rather low due to the low signal amplitude.

It is an object of my invention to provide a receiver of the general type outlined above which is relatively free from the disadvantages outlined.

15 It is a further object of my invention to provide a receiver for time modulated impulse trains which is relatively free from interference disturbances.

It is a still further object of my invention to provide a receiver for time modulated impulse 20 trains which does not require such sensitive detecting apparatus as was necessary in earlier proposed receivers.

According to a feature of my invention, the 25 objects are accomplished by providing means for regenerating or reshaping the received impulses before passing the energy through a selective band-pass filter. This is done by using the received impulse to initiate a new pulse with one edge thereof, and this new pulse is made of a predetermined duration independent of the signal 30 level. Moreover, the new impulses are preferably made of a predetermined substantially constant amplitude level.

According to a further feature of my invention, 35 the reshaping of the waves is controlled to yield square-topped waves having a duration equal to half a cycle of the harmonic to be selected, thus yielding a maximum power at the frequency of said harmonic.

40 A better understanding of my invention and the objects and features thereof may be had from the particular description made with reference to the accompanying drawing in which:

Fig. 1 is a set of curves used to explain the 45 feature of my invention;

Fig. 2 is a block diagram of a simplified receiver made in accordance with my invention; and

50 Fig. 3 shows a more detailed circuit diagram of a simple form of shaping circuit in accordance with my invention.

Turning first to Fig. 1, a brief explanation of the operation of the transmitter system described more fully in my above referred to application, Serial No. 386,282 will be given. The top curve 55 of Fig. 1 represents a group of impulses constitut-

ing three pairs, 1-2, 3-4 and 5-6. Impulses 1-2 and 3-4 are shown positioned most close to one another and impulses 5-6 are shown in their most widely spread position. It will be understood that the normal unmodulated position of these impulses is a position midway between the two extremes. Thus, it can be considered that the pairs of impulses 1-2 and 3-4 are shown modulated with the most negative signals while impulses 5-6 represent the highest positive signal. The details of this type of modulation system are completely described in my above-identified application and need not be repeated here since the present invention relates only to the receiving system.

The next lower curve A represents the impulses as they are received at a receiving point. It will be noted that impulses 1a and 2a form a pair in which the spacing is at its closest position while impulses 5a and 6a represent the impulses at their greatest spacing. The impulses are so spaced that the period T defined by the interval between 1a and 3a or the period of repetition of odd or even impulses is substantially constant. Thus, it is seen that each pair of impulses is repeated at a substantially constant period.

Since the impulses representing the time displaced modulation are either both moved toward each other from the normal reference axis or are both moved away from each other simultaneously, the signal may be translated by the use of a properly chosen harmonic frequency. It is, therefore, possible with this type of system to receive the signals by means of a sharply tuned filter which will pass only the particular related harmonics and the modulation signals immediately adjacent thereto. In such systems, however, a relatively high harmonic is preferably used in order that the energy level may change substantially for a slight impulse displacement. The amount of energy of such high harmonic in the received signal is relatively feeble and accordingly requires a more sensitive amplifier than is required to detect the entire impulse. Accordingly, I provide means for reshaping and enlarging the received impulses without disturbing their normal spacing prior to the harmonic selection so that stronger signal indications may be obtained.

This feature of my invention may be more readily understood by a further reference to Fig. 1 of the drawing. The leading edge of each of the impulses 1a to 6a inclusive as they are received causes the shaping circuit to be moved into operative position. The circuit then preferably remains in this operative position for a predetermined length of time when it again returns to normal unoperated position, thus producing square wave impulses such as shown at 1b, 2b, etc. of curve B. In the example illustrated, it can then be seen that if harmonic curve C is considered, impulses 1 and 2 will produce the impulses 1b and 2b which intersect the portions 1c and 2c of harmonic curve C. It is clear that in this position impulses 1b and 2b intersect parts 1c and 2c of equal length and opposite sign so that at the receiver the zero indication is obtained. This, of course, means that there is no signal energy at the harmonic frequency in this position. Impulses 3b and 4b are similarly positioned to intercept portion 3c and 4c of curve C. In the other extreme modulation position of the impulses (as represented by 5a-6a), square wave 5b-6b will be produced which intercept the portions 5c-6c of curve C. In this position it is seen that a con-

siderable energy component of the harmonic frequency will be derived from the waves 5b-6b. At the normal unmodulated position the impulses will be positioned midway between those shown in Fig. 1 at 1b and 2b and 5b and 6b. It is thus apparent that if the harmonic C, which in the example of Fig. 1 is the sixth harmonic of the period T, is used, that an amplitude swing of from zero at 1b-2b to a considerable value at 5b-6b will be obtained. Thus, the signal after passing through a filter tuned substantially to C may be detected by an ordinary amplitude detector.

In Fig. 2 is shown a block diagram of a receiver circuit in accordance with my invention. The incoming high frequency impulses are impressed on the input of the radio frequency and intermediate frequency amplifier 20. This amplifier preferably includes a first detecting means in order that extremely high radio frequencies may be reduced to a lower value. If the impulses are also amplitude modulated to convey a further message, these amplitude modulating signals may be detected in an amplitude detector 22 and impressed on earphones 23 or with proper amplification on to any form of sound translator.

Preferably, the time modulated impulses are passed from amplifier 20 to a clipper amplitude limiter 21. Such a limiter serves to clip off the lower part of the impulses where they tend to trail off reducing noise effects and to limit the amplitudes of the pulses to a constant level. It is clear that the clipping effect is the more important of the two so far as reduction of noise level is concerned. This amplitude limiter is especially desirable if the impulses have been amplitude modulated but is often desirable in any case since it may serve to cut off the parts of the impulses where the greatest noise level may be present. The limited impulses are then passed on to a shaping circuit 24 which imparts to these impulses the general form shown in curve B of Fig. 1. This shaping circuit will be described in more detail later. In order that impulses 1b, 2b, etc. may be given the square topped form, I preferably provide a further amplitude limiter 25. The limiter may be omitted, in which case the pulses will have a downward slope on their upper surface and slight shifting with respect to the harmonic curve C will then occur to compensate this effect. From limiter circuit 25 the impulses are passed through a band-pass filter 26 tuned substantially to a suitable harmonic after which they are detected in a detector 27 and reproduced in a sound translator 28. As shown in Fig. 2, sound translator 28 consists of head phones. It is clear, however, that with suitable amplification any type of translator may be used.

Impulses 1b, 2b, etc. are preferably made sufficiently wide to encompass substantially the entire scope of signals 1a and 2a, so that the ending of the square waves is not influenced by the trailing ends of the incoming pulses. If this is not convenient, some other precautions should be taken to render the time duration of the square waves delivered from the shaper independent of the signal applied to the input thereof. This is a very important feature of the invention; and whether the leading or trailing edge of the arriving pulses be made use of to determine the time of starting the square wave, the circuit should in either case be arranged so that the duration of these square waves will be independent of the duration or amplitude of the input signal.

The above feature has the very important advantage of substantially reducing the noise-to-

signal ratio. This may be most easily understood if it is noted that the previously known types of receivers (such as those disclosed in U. S. Patents 2,266,401 and 2,262,838 above mentioned or in copending U. S. applications Serial No. 425,108, filed December 31, 1941, by E. M. Deloraine and E. Labin for "Pulse transmission systems" and Serial No. 386,282 filed April 1, 1941, by Emile Labin for "Pulse modulation systems") were inherently more or less responsive to variations in the width of the received pulses as well as being responsive to variations in the time position thereof.

By the limiting and clipping of the received pulses these are converted into trapezoidal pulses with flat tops and with flat valleys between so that substantially the only influence of noise voltages of moderate strength is to very slightly vary the time positions of the sloping front and rear edges of the trapezoids. It is clear that if these front and rear edges could be made absolutely vertical, noise voltages could not displace the time positions of these edges. In practice, however, the slope of these edges cannot exceed a finite maximum depending upon the band width of the receiver. Noise voltages therefore are capable of slightly shifting the time positions of these sloping edges. One effect of these shifts of edges backward and forward in respect to time is that the width or duration of the trapezoid is varied, while another effect is that the mean position of the trapezoid in time is varied.

In view of the fact that the prior art types of receivers responded to both of these effects the response of these receivers to noise was very considerable. By deriving from the trapezoidal pulses waves having a constant duration and having a shape determined by say the leading edge of the arriving pulses the present invention eliminates that part of the noise effect due to variations in the width of the pulses.

It should be noted moreover that impulses such as shown at 1a and 2a, etc. of Fig. 1 are generally much steeper on their leading edges and tend to trail off on their trailing edges. For this reason the shaping network if controlled by the leading edges (as is preferred) tends to further reduce the noise-to-signal ratio which might otherwise exist. If, for any reason, control by the trailing edge is desired, the impulses may be passed through a differentiating circuit and a clipper before application to the multivibrator.

It should further be noted that for strongest signal production impulses 1c, 2c, etc. should be made to last for a period of time substantially equal to a half period of the chosen harmonic frequency. When these impulses are of this duration a shifting of their position produces the maximum change in energy level.

In Fig. 3 I have illustrated a suitable shaping network 24 including two vacuum tubes V1 and V2 connected to operate as a multivibrator. Tube V2 is normally biased to pass current, which current flowing through resistors 29 and 30 produces across resistor 30a voltage drops at the cathode of tube V1 just sufficient to maintain the bias of the grid of tube V1 at cut-off.

When an impulse arrives over a coupling condenser 31, a positive voltage developed across resistance 32 is applied to the grid of tube V1 causing this tube to become conductive. Tube V1 immediately applies a negative potential over a coupling condenser 33 to the grid of tube V2 causing this tube to be biased below cut-off and

driving the cathode of tube V1 negative so that the grid is further positive relative thereto. Accordingly, upon arrival of an impulse the ultimate positive value of signal is almost immediately arrived at. The output from tube V1 causes a voltage drop across resistance 36 which is passed on to the band-pass filter 26 preferably via limiter 25 (Fig. 2). After the first impulse passes the charge on condenser 33 leaks off through a resistor 34 until V2 again becomes conductive and the current through V1 is abruptly entirely cut off. The time constant of the circuit including condenser 33 and resistor 34 determines the duration of the operative condition of the shaping circuit 24 and as a consequence the duration of a pulse. This time constant may be changed by adjusting resistor 34 to the desired value. The adjustment of resistor 30 may serve to vary the cut-off points of the tubes V1 and V2 and thus to adjust the duration of the impulse without changing the time constants of circuits 33, 34. The square wave impulses produced in this multivibrator circuit 24 are taken off across grid cathode resistor 36 and applied to the input of the band-pass filter 26 of Fig. 2.

It is clear that other forms of shaping circuits may be designed than the simple multivibrator circuit shown herein. The prime requisites of my invention are that the shaping network be such that it will be brought into operation by one of the edges of the received impulses and will be made to continue in operation for a period of substantially fixed length. It is further clear that if desired, a receiving circuit shown in Fig. 2 may be provided with other apparatus for blocking out all signals between the times when the impulses are to be received as disclosed in my above referred copending application.

Many other modifications of my invention may occur to those skilled in the art and it is considered that all of these obvious modifications of my invention are included in the scope thereof.

What is claimed is:

1. A receiver for detecting time modulated impulse energy wherein the impulses are modulated by pairs at least one of the pulses of each pair being time displaced relative to the other between two limits according to the instantaneous value of the modulating signal, one of such limits being defined by a constant timing interval; said receiver comprising means for shaping the received impulses into substantially constant duration impulses, filter means passing substantially only a band of frequencies immediately about a harmonic of said constant timing interval, whereby energy of said constant duration impulses is passed according to the time displacement thereof from one of said limits, and means to detect the energy passed by said filter means.

2. A receiver according to claim 1 wherein said shaping means comprises means triggered by the leading edge of each of said received impulses for producing said constant duration impulses.

3. A receiver according to claim 1 wherein said shaping means comprises means triggered by the leading edge of each of said received impulses for producing said constant duration impulses and means for limiting the impulses to a substantially fixed amplitude.

4. A receiver according to claim 1 wherein said shaping means comprises a multivibrator circuit arranged to be triggered from a normal condition in one direction by the leading edge of each received impulse and to return to said normal

condition a predetermined time after movement in said one direction.

5. A receiver according to claim 1 wherein the shaping means is adjustable for obtaining output impulses of a duration equal to a half period of the harmonic of said constant timing interval.

6. A receiver for segregating and detecting time modulated impulse energy wherein the impulses are modulated by pairs at least one of the pulses of each pair being time displaced relative to the other between two limits according to the instantaneous value of the modulating signal, one of such limits being characterized by a constant timing with respect to pulse pairs; said receiver comprising amplitude limiting means for limiting the received impulses to a predetermined level to remove any amplitude modulation effects therefrom, means for shaping the amplitude limited impulses into substantially constant duration impulses, and filter means passing substantially only a band of frequencies close about a harmonic of said constant timing characteristic of the pulse pairs whereby energy of said constant duration impulses is passed according to the time displacement thereof from one of said limits, and means for detecting the amplitude of the energy passed by said filter means.

7. A method of translating into amplitude modulated energy a source of time modulated impulses wherein the impulses are modulated by pairs at least one of the impulses of each pair being time displaced relative to the other between two limits according to the instantaneous value of the modulating signal, one of such limits be-

ing characterized by a constant timing with respect to the pulse pairs; which method comprises shaping the impulses into substantially constant duration impulses and passing energy of the constant duration impulses in amounts according to the time displacement thereof with respect to a harmonic of the constant timing characteristic of the pulse pairs.

8. The method defined in claim 7 wherein the duration of said constant duration impulses is selected equal to a half period of said harmonic.

9. The method defined in claim 7 wherein the shaping operation is characterized by timing the leading edges of each constant duration impulse with the leading edge of the corresponding received impulse.

10. The method defined in claim 7 wherein the shaping operation is characterized by timing the leading edges of each constant duration impulse with the leading edge of the corresponding received impulses, and the duration of said constant duration impulses is selected equal to a half period of said harmonic.
